UNITED STATES PATENT OFFICE.

SILVIO COCANARI, OF ROME, ITALY, ASSIGNEE TO L. GEVAERT ET CO., OF VIEUX-DIEU,
NEAR ANTWERPEN, BELGIUM.

ROLL FILM FOR PHOTOGRAPHIC PURPOSES AND ITS WRAPPING.

Application filed September 3, 1921. Serial No. 498,542.

(GRANTED UNDER THE PROVISIONS OF THE ACT OF MARCH 3, 1921, 41 STAT. L., 1313.)

To all whom it may concern:

Be it known, that I, SILVIO COCANARI, technician, a citizen of the Kingdom of Italy, and resident of Rome, Italy, have invented 5 certain new and useful Improvements in and Relating to Roll Films for Photographic Purposes and Their Wrappings (for which applications have been filed in Belgium Apr. 30, 1920; Germany, June 1, 1920; Spain, May 10 29, 1920; Switzerland, May 25, 1920; Italy May 26, 1920; France May 21, 1920; and England May 21, 1920); and I do hereby declare the following to be a full, clear, and exact description of the invention, such as 15 will enable others skilled in the art to which it appertains to make and use the same, reference being had to the accompanying drawings, and to letters or figures of reference marked therein, which form a part of this 20 specification.

This invention relates to roll films or the like and more particularly to roll films used in conjunction with photography.

The roll films used in photography are 25 generally wound on reels or bobbins together with bands of protective paper forming the wrapping. This wrapping is usually composed of a band of red paper or a band of black paper or a band of black paper covered with a band of red paper. In order to 30 enable the film to be inserted in the apparatus without the use of a dark chamber, the wrapping band or bands are made of such a length that they extend beyond the ends of 35 the films by a certain predetermined length. The commencement of the film, that is the end located on the outside of the bobbin when the latter is inserted in the photographic apparatus, is gummed to the wrapping paper, for example, by means of a 40 gummed label. The opposite end however, which will hereinafter be called the final end must remain free in order that the film may always remain quite flat against its wrapping paper whilst it is being unwound in 45 the apparatus and wound up in an opposite direction on another reel, in spite of the difference in length which will obviously occur between the film and its protective wrapper 50 when they are wound up together.

After the film has been exposed it is wound in the opposite direction upon a bobbin with its final extremity on the outside of the reel.

If the film is to be developed in a developing apparatus in daylight and without the use of a dark chamber, it is necessary to be able 55 to wind the film afresh on the metal reel or bobbin of the developing apparatus. Therefore in order that the film may, during this operation, be drawn by its protective wrapper 60 it has been necessary with films hitherto employed, to stick the final extremity of the film to its protective wrapper by means of a gummed label. In order to effect this gumming, the end of the paper of the film 65 must be unwound, and in spite of the precautions which have always been taken there has always been a risk of exposing the end 70 of the film to the light.

The present invention avoids this preliminary gumming of the final end of the film on the paper by an arrangement such that the final end of the film is attached permanently to its protective wrapper at the same time permitting a relative slipping action to 75 take place between the film and its wrapper. To this end according to this invention the final extremity of the film is in the form of a tongue which is inserted in a slot in the protective wrapper. This tongue is permitted 80 to slide freely in the slot to allow of the displacement of the film relatively to its wrapper at the same time securing sufficient relative fixity between the film and the wrapper to prevent its being drawn with the 85 paper when wound on the reel of the developing apparatus. The adherence of the tongue to the paper is also increased by the tendency which the material of the film has to wind up on itself. 90

The tongue may be so designed and prepared that in addition to the function already set forth it may take the form of a label by which the identification of the film may be determined easily by writing or inscribing in any suitable manner the name, place, date or the like particulars. In order that the sensitive face of this tongue, which may be exposed to the light, shall not become black when developed it may be protected by coatings or any other suitable means. 95

The invention will be more readily understood when read in conjunction with accompanying drawings in which:— 100

Fig. 1 is a view of the film unwound, 105

Fig. 2 a view of the film partially unwound after it has been exposed in the photographic apparatus.

Fig. 3 shows the final extremity of the sensitive face of the film.

The film 1 is shown wrapped with its back against the black surface 2 of its protective wrapper which is coated with a sheet of red paper 3. The ends of the wrapper extend 10 beyond the film to enable them to be fixed to the reels or bobbins. The end of the film is stuck to the protective wrapper by means of a gummed label 4 whilst the final extremity forms a tongue 5 which is inserted freely in 15 a slot 6 in the protective wrapper.

After the film has been exposed, inscriptions for the identification of the film may be made on the back of the tongue 5, by unwinding, with precaution, the film until the 20 back of the tongue appears (Fig. 2). In order to ensure that a good inscription is made upon the tongue 5 of the film it may be subjected to a suitable treatment, for example, covered with a matte coating, or be 25 rendered matte by a pouncing or the like.

The sensitive face of the tongue 5, which has been exposed to the light during these operations of inscriptions, will become black in the developing bath, and consequently in 30 order to avoid this disadvantage, the sensitive face of the tongue 5 may be covered with a layer of protective varnish made of collodion or resin (Fig. 3) or an impervious label gummed to the film by means of gum- 35 lacquer.

What I claim is:—

1. A roll film for photographic purposes comprising a film, a protective wrapper for said film having one end of the film connected therewith, the free end portion of the 40 film being provided with a tongue extending longitudinally of the film and said protective wrapper having a transversely extending slot receiving said tongue to hold the 45 free end portion of the film in engagement

with the protective strip and permit sliding movement of the film longitudinally of the wrapper.

2. A roll film comprising a film, a protective wrapper having a transverse slot and to 50 which the film is fixed at one of its ends, permitting the film to slide relative to the wrapper, and a longitudinally extending tongue provided at the other end of the film, said tongue being adapted to be passed 55 through the transverse slot in the protective wrapper, and the back of said tongue being prepared to receive inscriptions.

3. A roll film for photographic purposes 60 comprising a film, a protective wrapper having a transverse slot and to which the film is fixed at one of its ends, permitting the film to slide relative to the wrapper and a longitudinally extending tongue provided at the other end of the film, said tongue being 65 adapted to be passed through the transverse slot in the protective wrapper, and means for protecting the sensitive face of said tongue against light

4. A film roll comprising a film, a protective wrapper, means for fixing one extremity 70 of the film to the wrapper, a tongue provided at the other end of the film and adapted to be inserted into a slot in the protective wrapper, the back of said tongue 75 being prepared to receive inscriptions.

5. A film roll comprising a film, a protective wrapper, means for fixing one extremity 80 of the film to the wrapper, a tongue provided at the other end of the film and adapted to be inserted into a slot in the protective wrapper, and means for protecting the sensitive face of the tongue against light.

In testimony whereof I affix my signature in presence of two witnesses.

SILVIO COCANARI.
